UNITED STATES PATENT OFFICE.

SAMUEL E. TOMPKINS AND JOHN F. GOODSELL, OF NEWARK, N. J.

DESIGN FOR ORNAMENTATION FOR HARNESS.

SPECIFICATION forming part of Design No. 16,114, dated May 26, 1885.

Application filed January 21, 1885. Term of patent 7 years.

To all whom it may concern:

Be it known that we, SAMUEL E. TOMPKINS and JOHN F. GOODSELL, citizens of the United States, residing at Newark, in the county of 5 Essex and State of New Jersey, have invented and produced a new and Original Design for Trimming or Ornamentation for Harness; and we do hereby declare the following to be a full, clear, and exact description of the invention, 10 such as will enable others skilled in the art to which it appertains to make and use the same, reference being had to the accompanying drawings, and to letters of reference marked thereon, which form a part of this specification.

15 Figures 1 and 3 are edge views of browbands, partly in section, ornamented with our trimmings. Fig. 2 is a plan of a harness-rosette. Fig. 4 is a plan of a pad-housing; and Fig. 5 is a plan of a bridle-winker, said 20 figures illustrating the more important harness parts embodying our design.

Our design relates to trimmings or ornamentation for any or all of the various parts of a harness; and it consists of a spiral, flattened as shown, so that the individual coils or 25 helices thereof lap over and rest upon each other.

In the drawings, *a* represents the several individual coils, which are flattened or bent down 30 upon themselves, as is clearly shown in the various figures. By thus flattening the spiral the visible and ornamental effect is very much enhanced over the ordinary spiral, as the coils are caused to overlap each other and form an

ornament or trimming which presents the same appearance its entire length, no matter how applied, whether on a circle or any curved surface.

Only a few of the various parts of the harness have been shown to illustrate the application of our ornamentation or trimming; but it will be readily understood that it can be applied to any or all other points thereof.

The preferred form of application has the coils or spiral set back a little way from the 45 edge, so that both the edge of the harness and the edge of the coil are apparent to the observer. The edge of the harness may have any additional trimming desired, as a roll or line of stitching.

50 What we claim as new is—

The design for the ornamentation of harness, consisting of a piece of harness having thereupon the flattened spiral convolutions overlapping and resting upon each other and 55 placed at a slight distance from the edge of the piece, so that both the plane edge of the piece and the scalloped edge of the spiral show out in contrast, as set forth.

In testimony that we claim the foregoing 60 we have hereunto set our hands this 19th day of January, 1885.

SAM. E. TOMPKINS.
JOHN F. GOODSELL.

Witnesses:

CHARLES H. PELL,
FREDK. F. CAMPBELL.
